CAR JACK

Paul Kunath, Dresden, Germany

Application March 20, 1935, Serial No. 12,018
In Germany March 27, 1934

4 Claims. (Cl. 254—1)

This invention relates to a car jack to which supports are secured to prevent it from slipping or toppling over.

According to the invention, one or several supports engage a rotatable ring or flange of the jack and are thus rotatably arranged on the latter. The supports, or a majority thereof, are capable of adapting themselves to ground conditions and of being adjusted so that they take up the lateral pressure exerted by the car upon the jack which, even if it is placed on slanting ground, cannot slip any more, and the jacked up car is therefore prevented from tilting.

By way of example, the invention is illustrated in the accompanying drawing, in which Figure 1 is a side view of the jack; Fig. 2, a front view of a support; Figs. 3 and 4 show the arrangement of a plurality of supports; and Figs. 5 and 6 show how a support is automatically raised 20 and lowered.

The jack according to the invention may have a hydraulic, pneumatic or mechanical drive, the construction shown employing a toothed wheel drive. The jack comprises the standard 1, the base plate 2, the extensible ram 3 and the lifting head 4, the ram 3 being elevated by the turning of the toothed wheels 5 and 6. At the top end of the standard 1, as indicated in Fig. 3, or at the top end of the ram 3, as shown in Fig. 1, and in case of a plurality of telescopic rams at the lowest ram portion, a ring or flange 7 is rotatably disposed to which a support 8 or a plurality thereof, as shown in Figs. 3 and 4, are articulated by means of ball joints 9 or hinge bolts. To insure a firm stand of the supports they have forked ends 10.

If the car to be lifted is in an inclined position, it is possible, while the jack is placed under the car, to bring the support or supports 8 easily into any supporting position by turning the ring or flange 7. The arrangement of the jack with the support or supports 8 under the car is facilitated by lifting the support or supports by means of the disc 11 which has a large bore 12 and is placed laterally under the support or supports. A spring 13 presses the disc 11 up against the support 8 which is thus raised approximately horizontally and clamped by the spring, as indicated in Fig. 5. When the ram 3 is elevated from the position of Fig. 5, the disc 11 is pressed up by the spring 13 which is therefore relieved of tension, so that the disc 11 is

pushed laterally by the weight of the support 8, as indicated in Fig. 6, which now rests on the floor or ground and is pressed into it. When the support 8 is firmly pressed into the ground, the ring or flange 7 cannot rotate any more, and the support firmly engages the standard 1 and prevents it from toppling over.

The support or supports 8 may be extensible within themselves to permit telescoping for transport and facilitate packing of the jack. 10

I claim:—

1. A car jack, comprising a standard, a movable ram in said standard, means for moving said ram, a rotatable ring at the top end of the standard, a plurality of supports for laterally supporting the jack to prevent toppling over and slipping, and means for articulating said supports to said ring to insure universal motion of said supports. 15

2. A car jack, comprising a standard, a movable ram in said standard, means for moving said ram, a rotatable ring on said ram, a plurality of supports for laterally supporting the jack to prevent toppling over and slipping, and means for articulating said supports to said ring to insure universal motion of said supports. 20

3. A car jack comprising a standard, a movable ram in said standard, means for moving said ram, a rotatable ring at the top of said standard, a plurality of supports having pointed lower ends for laterally supporting the jack to prevent toppling over and slipping, means for articulating said supports to said ring to insure universal motion of said supports, a disc disposed on said ram between said standard and rotatable ring and provided with a bore larger than the horizontal section of the ram to permit shifting the disc laterally to a position in which it engages one or two supports, and a spring disposed under said disc and adapted to press said disc up against the supports to raise them and thus facilitate the arrangement of the jack underneath a car, said spring being untensioned by the elevation of the ram and said disc being laterally shifted by the support or supports it has lifted to permit all supports to engage the ground with their pointed ends. 30 35

4. A car jack according to claim 3, wherein the supports have forked lower ends which with 40 45 their points enter the ground.

PAUL KUNATH.
